MOSES ADSIT, OF FORREST, NEW YORK.

Letters Patent No. 77,433, dated May 5, 1868.

IMPROVEMENT IN DRAUGHT-ATTACHMENT.

The Schedule referred to in these Letters Patent and making part of the same.

TO ALL WHOM IT MAY CONCERN:

Be it known that I, MOSES ADSIT, of Forrest, in the county of Clinton, and State of New York, have invented a new and improved Draught-Attachment for vehicles; and I do hereby declare that the following is a full, clear, and exact description thereof, which will enable those skilled in the art to make and use the same, reference being had to the accompanying drawings, forming part of this specification.

This invention relates to a new and useful improvement in draught-attachments for all kinds of vehicles which are drawn by horses, and has for its object the equalizing of the draught, by admitting of the whiffle-trees being automatically adjusted in relation with the double-tree under pull of the team, and in such a manner that if one horse of a team has an inclination to pull more than his share, his labor will be proportionably increased, while the other horse will have his labor correspondingly decreased, and will feel encouraged to exert himself and pull up even with the more ambitious one.

By this means the device will not only have a tendency to correct a team which pulls unevenly for the time being, but will also have a tendency to break or train an unmatched team, so that the two horses of the same will in a short time be permanently matched, so far as equal draught is concerned. In the accompanying sheet of drawings—

Figure 1 is a plan or top view of my invention.

Figure 2, a section of the same taken in the line x x , fig. 1.

Similar letters of reference indicate corresponding parts.

A represents a draught-pole, which does not require any peculiarity in its construction, and B is a double-tree, secured to the draught-pole by a bolt, a , which passes through the front end of a metal strap, C, the rear part of which is bolted to the draught-pole, and is bent upward, so as to extend over the double-tree, to the front edge of the same, as shown in fig. 2.

This double-tree is constructed in a peculiar manner as follows: To the rear side of the same there is attached a metal bar, D, the ends of which are bent around the ends of the double-tree, and firmly bolted thereto, a groove or rebate being made in the upper and lower surfaces of the double-tree to receive plates b b , which are somewhat shorter than the double-tree, in order that the latter may have a certain degree of longitudinal play independently of them.

To the ends of these plates b b clevises E E are attached, the bolts c of which pass down through oblong slots, d , in the whiffle-tree, to admit of the independent play of the double-tree, and at the same time allowing said bolts to connect the two plates. The whiffle-trees to which the horses are attached are connected to these clevises.

The strap C has a bolt, e , passing through it, which extends through an oblong slot, f , in the double-tree, and also through the two plates b b and into the draught-pole A, (see fig. 2.) The oblong slot f , like the slots d of the bolts c , admits of the independent play of the double-tree, while the bolt e forms a positive connection between the plates b and the strap.

This arrangement admits of the clevises E being thrown respectively further from and nearer to the bolt a of the double-tree, as the latter is moved from a right-angular position relatively with the draught-pole, the clevis at the forward end of the double-tree being brought nearer the draught-pole than the opposite end, and the leverage power of the forward end proportionably decreased. Hence the most ambitious horse will, in consequence of the increased draught or labor put upon him by this automatic arrangement, check himself, while the less ambitious one, in consequence of the decreased labor, will be stimulated to pull ahead.

Strictly speaking, this automatic adjustment of the whiffle trees is due to the turning-movement of the double-tree, the plates b in reality having no longitudinal movement in themselves, as they are connected by the bolt e to strap C, and can swing or turn with the double-tree, but not being positively connected with it, or not turning from the same bolt a as a centre, (e being the bolt of the plates b ,) the result specified is obtained.

I would remark that the bolts which pass through the double-tree may be provided with friction-rollers, in order to avoid friction in the working of the device.

I claim as new, and desire to secure by Letters Patent—

The plates *b b*, sliding in grooves upon the top and bottom of the double-tree *B* in front of the band *D*, said plates *b* secured together at their ends and centres by the bolts *c e*, which slide in the slots *d f* of the double-tree, all constructed and arranged to operate as herein described for the purpose specified.

MOSES ADSIT.
